UNITED STATES PATENT OFFICE

GUSTAVE C. ABERLE, OF GLENSIDE, PENNSYLVANIA

DESIGN FOR A STOCKING

Application filed October 14, 1931. Serial No. 41,387. Term of patent 3½ years.

To all whom it may concern:

Be it known that I, GUSTAVE C. ABERLE, a citizen of the United States, residing at Glen-side, county of Montgomery, and State of Pennsylvania, have invented a new, original, and ornamental Design for Stocking, of which the following is a specification, reference being had to the accompanying drawings, forming part thereof.

Figure 1 is a side diagrammatic elevation of the stocking.

Figure 2 is a magnified showing of a portion of the cuff of the stocking shown in

Figure 1, the circular line indicating in a dia-grammatic manner the circular edge of a magnifying glass.

Figure 3 is a magnified showing of a por-tion of the leg of the stocking shown in Figure 1, the circular line indicating in a dia-grammatic manner, the circular edge of a magnifying glass.

I claim:

The ornamental design for a stocking as shown and described.

GUSTAVE C. ABERLE.
